UNITED STATES PATENT OFFICE.

FRANK L. G. PAGE, OF NEW YORK, N. Y., ASSIGNOR TO POWER SPECIALTY COMPANY,
OF NEW YORK, N. Y., A CORPORATION OF NEW YORK.

SUPERHEATER.

1,245,263.

Specification of Letters Patent. Patented Nov. 6, 1917.

Application filed January 5, 1916. Serial No. 70,369.

To all whom it may concern:

Be it known that I, FRANK L. G. PAGE, a citizen of the United States, residing at New York, county and State of New York, ⁵ have invented certain new and useful Improvements in Superheaters, of which the following is a full, clear, and exact description.

The invention which constitutes the subject matter of this application relates to an improvement upon the superheater device shown and described in the patent to Primrose, No. 1,152,839, granted September 7, 1915. The invention pertains to a construction in which there are provided at least five horizontal rows of superheater elements projecting rearwardly into enlarged fire tubes and in which one superheating unit or element, although its end portions be substantially ¹⁵ behind other end portions, may be individually removed for repair or replacement without necessarily removing any of the other units.

In the drawings,

Figure 1 is a front view of the device illustrating the relation of the superheater to the smoke box, fire tubes and tube sheet of the boiler.

Fig. 2 is a front view of the device taken substantially on the line 2—2 of Fig. 1.

Fig. 3 is a top plan view in section of the header, illustrating the connections between the header and superheating units and taken substantially on the line 3—3 of Fig. 1.

Referring to the drawings in detail, the reference character 10 designates the forward portion of a locomotive or stationary boiler, provided with the usual fire tubes 11, smoke box 12, tube sheet 13 and dry pipe

14. The superheater comprises a saturated steam header 15 into which the dry pipe 14 discharges, the superheated steam header 16, and the superheating elements or units which project rearwardly into the fire tubes 11 and the inlet and outlet ends of which are preferably expanded respectively into the inlet and outlet headers 15 and 16.

The fire tubes are arranged in vertical and horizontal rows, as is usual in boiler construction, but only five horizontal rows are utilized so far as the present drawings are concerned to elucidate my invention.

In order to explain my invention, I show in Fig. 2 three vertical rows, A, B and C, of fire tubes and a corresponding number of

vertical rows of superheating units therein, and for convenience of description I designate the units in each vertical row as 1^a, 2^a, 3^a, 4^a, 5^a; 1^b, 2^b, 3^b, 4^b, 5^b; and 1^c, 2^c, 3^c, 4^c, 5^c, respectively, it being of course understood that the arrangement in one row is the same as the arrangement in the other rows. Take the middle row as seen in Figs. 2 and 3 and suppose it is desired to remove unit 1^b. In this case, it is only necessary to disconnect the ends thereof from the header and move it straight forwardly between 2^b and 4^b on the one hand and 3^b and 5^b on the other. To remove unit 2^b (assuming the others to be in normal position) disconnect the ends thereof from the headers, turn said ends slightly to the left, that is, toward 1^b, then withdraw between 3^b and 5^b on the one hand and 4^b on the other. To remove unit 3^b (assuming the others to be in normal position) disconnect the ends thereof from the headers and withdraw the same between the superheated ends of 5^b and 1^b. To withdraw 4^b, assuming the other units to be in place: The superheated end of 4^b comes straight out without interference, it being located forwardly of all the other ends of those in the vertical row. The other end, however, is moved straight for a slight distance, then moved so as to be withdrawn between 3^c, 1^c and 5^c on the one hand and 2^b on the other. To remove 5^b (assuming all other units to be in place): The superheated end of 5^b comes straight out, there being no interference to this movement; the other end is disconnected and withdrawn between the saturated ends 4^a and 3^b and then between the superheated ends 3^b and 1^b on the one hand and 2^a and 4^a on the other.

In designing a superheater of this character, due consideration may be given to the fact, owing to the flexibility of the units and particularly the ends thereof, that the units can be arranged into closer proximity to each other than what they otherwise could.

The end portions of unit 1^b are straight. The units 2^b, 3^b, 4^b and 5^b are bent outwardly to form a path or lane for the withdrawal of the units, as will be understood. This path or lane is also desirable for the more efficient discharge of the furnace gases from the boiler tubes in which the superheater coils are contained.

What I claim is:

1. The combination with a boiler having five fire-tubes arranged one above another in substantially the same vertical plane, of a header provided with steam chambers, and a superheater unit arranged in each of said fire tubes and having upwardly projecting end portions which are expanded into said chambers, the end portions of a plurality of said units being located substantially behind one another, and any of said units adapted to be removed independently of the others.
2. The combination with a boiler having five fire tubes arranged one above another in the same vertical plane, of a header provided with steam chambers, and a superheater unit projecting rearwardly into each of said fire-tubes and having upwardly projecting end portions which are expanded into said chambers with the end portions of alternate units lying on opposite sides of a plane passing through the axes of said
3. The combination with a boiler having fire tubes arranged in horizontal vertical rows, each of the vertical rows comprising five fire tubes, of a header provided with steam chambers, and superheater units arranged in each of the fire tubes and having upwardly projecting end portions which are expanded into said chambers, the end portions of a plurality of the upper units being located substantially behind the end portions of the lower units, and any of said units adapted to be removed from the boiler independently of the others.

In testimony whereof I hereunto affix my signature.

FRANK L. G. PAGE.
